(57) **CLAIM**

The ornamental design for a wheel, as shown and described.

DESCRIPTION

FIG. 1 is a front elevational view of a wheel showing our new design; and,

FIG. 2 is a perspective view thereof.

The broken line showing of the circles in a pentagonal pattern at the hub is included for the purpose of illustrating environment and forms no part of the claimed design.

1 Claim, 1 Drawing Sheet

FIG. 1

FIG. 2
